TWO-WIRE ALARM OR CONTROL SYSTEM

Olof Ingemar Harald Ekman, Stockholm, Sweden

Application June 10, 1952, Serial No. 292,706

5 Claims. (Cl. 340—213)

This invention relates to a two-wire alarm or control system, and more particularly to an alarm or control system, in which the two wires form a continuous long loop circuit which originates at and returns to a central station, and the long loop is subdivided into a number of serially connected sections by double pole switches which are shunted at the central station side by conductive impedances.

Control and alarm circuits of the two-wire type and with shunt impedances at section switches are described in a patent to Hans T. Nicou, No. 2,294,043, August 25, 1942, and in my copending application Serial No. 290,432, filed May 28, 1952. A number of two-pole thermo-contacts or thermal switches are arranged in each section of the loop circuit, and both wires are opened when a thermo-contact is opened automatically by a predetermined temperature rise, or when one of the section switches is opened manually. A storage battery at the central station normally establishes direct currents in parallel through the two wires and, after opening of the loop circuit, the two terminals at each end of the loop circuit are connected to the opposite terminals of a current source. The impedances at the section switches are now in parallel in each of the wire circuits at opposite sides of the opened section and the number of impedances at each side of the opened switch is measured by bridge methods to identify the section of the loop circuit which is open.

The prior practice has been to employ capacitive impedances at the section switches as there appeared to be no practical solution for the contradictory design requirements that the section impedances should be of high ohmic resistance to avoid an effective short-circuiting of the two wires of a long loop which includes a number of sections, and should be of low ohmic resistance to insure a measurable distinction between the resistance of a single impedance and the relatively low insulation resistance of a long loop circuit located in a region of high humidity, acid fumes or other adverse conditions. With capacitive section impedances it is of course necessary to provide a source of alternating current to energize the measuring circuits. The apparatus employing capacitive impedances has been satisfactory and is currently in use, but the requirement for a source of alternating current for the impedance-measuring bridges can be eliminated and other advantages can be had if the section impedances are of resistive or inductive type.

Objects of the present invention are to provide alarm and/or control circuits of two-wire shunt-impedance type in which the shunt impedances are conductive. Objects are to provide two-wire alarm or control circuits with section impedance of conductive type, and which are free from the limitations and disadvantages attendant upon the prior long-loop circuits employing conductive impedances. More specifically, objects are to provide alarm or control systems of the character stated in which the section impedances take the form of a resistance or an inductance in series with a rectifier and the circuit arrangement is such that the impedances are non-conductive during normal operation of the circuit but conductive to reversed polarity current upon a two-wire break in the loop circuit.

These and other objects and the advantages of the invention will be apparent from the following specification when taken with the accompanying drawing in which the single figure is a fragmentary circuit diagram of an automatic fire alarm circuit embodying the invention.

2.

In the drawing, the reference characters *a* and *b* identify the two wires of a long loop circuit which is divided into a number of sections, for example ten sections I to X, by a number of section units or boxes SI which preferably each include a normally closed double pole switch *S* which may be opened manually to actuate the alarm system. There is a station indicator at the start of each section, it being assumed for convenience of description that the loop circuit starts at the positive terminal of a storage battery 11 at the central station and returns to the negative terminal of the battery. A number of thermo-contacts *T* are in series in the two-wire line in each section, the number of the thermo-contacts depending upon the length of the section and the condition or character of the premises through which the section extends. The thermo-contacts *T* are double pole normally closed switches which open automatically when the temperature exceeds a preselected value, and they preferably are of the type disclosed and claimed in my prior Patent No. 2,599,441, granted June 3, 1952.

A relay *R_a* is in series in a wire adjacent the start of the loop circuit, and a relay *R_b* is similarly in series in wire *b* at the end of the loop circuit. These relays are closed manually to place the system in operation, and have holding contacts *12a* and *12b* respectively for maintaining them energized so long as there is no break in the wires *a* and *b* respectively, and no short-circuit of the wires on each other. Relays *R_a* and *R_b* each have a plurality of sets of contacts for signal and control purposes, including sets *13a* and *13b* respectively with front contacts operative when the relays are energized, to complete the wire *a* circuit to the negative terminal of the battery 11 and the wire *b* circuit to the positive battery terminal. Wire *a* of the loop circuit is returned directly to the negative battery terminal but a voltage-dropping resistance *R* is between the front contact of set *13b* and the positive terminal.

At each fire alarm box or station indicator SI, the central station side of the switch *S* is bridged by a conductive impedance *CI* in series with a rectifier *RT* of dry plate or disk type, the rectifier being so polarized as to block current flow from wire *b* to wire *a* when, as above stated, wire *b* is at the higher positive potential. The conductive impedance may be an inductance or iron-cored choke or, as illustrated, may be a resistance.

As is known in two-wire systems of this general type, the relays *R_a* and *R_b* will each be de-energized upon a break in wires *a* and *b*, respectively, and relay *R_b* will be released by a short circuit between the two wires. Relay *R_a* is not released by a short-circuit as it will then be shunted by the resistance *R* which is of about 3,000 ohms resistance whereas the resistance of relay *R_a* is about 1,500 ohms. As above noted, the relays have sets of switch contacts not shown, for closing signal circuits to indicate the release of either relay. The station attendant is thus advised of a fault on the system and should take appropriate steps to locate and remove it.

A fire alarm signal is to be sounded only in the event of a simultaneous break of both wires, either by a manual opening of a switch *S* at one of the station units SI or by the automatic opening of one of the thermo-contacts *T* by an abnormally high temperature. When this occurs, the ends of the wires are separated from the battery terminals by the relays and connected into Wheatstone bridges which, when balanced, identify the particular section which has opened, there being a bridge *W* for the portion of the loop at the left of the break and a similar bridge, not shown, at the right side of the break. The circuit arrangements for establishing the measuring circuits are as follows: The back contact of set *12a* of relay *R_a* is connected by a lead 14 to junction *A* of bridge *W*, and the back contact of set *13b* of relay *R_b* is connected by a lead 15 to an adjacent bridge junction *B*. Similarly, the back contacts of switch sets *12b* of relay *R_b* and *13a* of relay *R_a* are connected to leads 14, 15 to the other bridge. The blades of sets *12a* and *13b* are connected to the wires *a* and *b*, respectively, and the simultaneous release of both relays thus connects the lefthand portion of the opened line into the bridge *W* as one side arm thereof.

The two adjacent arms *BC* and *CD* are comprised by

impedances of equal ohmic resistance and which preferably are the windings of relays 16, 17 respectively having contacts in appropriate fault signal circuits, not shown. The arm DA of the bridge is an adjustable impedance or "station selector" SS comprising ten conductive impedances, specifically resistances r when the conductive impedances CI of the several stations are of resistive type as shown. A contact blade c may be turned by a knob d to connect the resistances in parallel, step-by-step, until the bridge is balanced by the same number of resistances r as there are conductive impedances CI in the bridge arm AB.

The cross-arm AC of the bridge contains a relay 18 which drops out at bridge balance, the relay having contacts in signal circuits, not shown, for indicating that condition. The negative terminal of the battery 11 is connected to junction B of bridge W by a lead 19, and the positive terminal is similarly connected to junction D by a lead 20. The bridge W is thus continuously energized and the relays 16, 17 will release to give a fault signal in case the bridge should be de-energized.

The method of operation of the described alarm system is as follows, it being understood that the circuit diagram illustrates the circuit in normal operating condition.

It is to be noted that the positive potential on the wire a beyond the relay R_a will be relatively low, say of the order of 2.5 volts or less when battery 11 is a 24 volt battery, as the resistance of the relay R_a may be of the order of 1500 ohms and, in any event, constitutes the major portion of the total series resistance of the wire a circuit. The positive potential on the wire b along the several sections will be substantially higher in view of the voltage drops across the relay R_b and the series resistance R . If the resistance of relay R_b is about 1500 ohms and that of resistance R is about 3,000 ohms, the positive potential on wire b along the several sections of the loop circuit will be about 8 volts. The relative polarities of the wires a , b reverse, however, when connected into the bridge upon an opening of a switch S or a thermo-contact T . The wire b is then at zero potential since it is connected through leads 15 and 19 to the negative terminal of the battery 11. Wire a is at a more positive potential and the rectifiers therefore are conductive.

The requirements for reliability in operation and sensitivity of open-section identification are thus satisfied by conductive shunt impedances CI since the provision of the rectifiers RT imparts a substantially infinite resistance to the impedances so long as the system is in normal condition, and the reversal of the polarities of the wires a and b upon an opening of the two-wire loop circuit substantially eliminates the rectifiers RT from consideration and each shunt path assumes its normal resistive or inductive impedance. Values as low as 1,000 ohms, which is convenient for clear station identification, are entirely practical with no risk of a false indication of a short between the wires.

While only resistive impedances CI have been illustrated, it is apparent that an inductive type such as iron-cored inductances or chokes may be employed. The latter have the advantage that the long loop circuit may then carry telephone or supervisory signals. It is to be understood that a plurality of loop circuits of the described type may be associated with a central station, and that various refinements in the bridge balancing impedance, as disclosed in my copending application, may be employed without departure from the spirit and scope of my invention.

In order to compensate for the ohmic resistance of the lines between the station indicators SI, especially in the case where such lines are very long, it is preferable to reduce the impedance of the station indicators progressively in the direction away from the first station at the beginning of Section I and in such manner that the amount of resistance from the beginning of the line to each station indicator plus the impedance of such station indicator will always be of equal value and hence correspond to the equal impedance characteristics of

the several impedances r included in the station selector SS.

I claim:

5 1. A control or alarm system of the type including a normally closed two-wire circuit connected as a loop across a direct current source at a central station, shunt impedances connected between the wires of said circuit at spaced points to divide the circuit into a plurality of sections, relay means included in each wire of said two-wire circuit and de-energized upon an opening thereof, means additional to said relays developing a normal potential difference between said wires along the loop circuit, and means operative upon a simultaneous opening of said relays for connecting into a direct current measuring circuit one end portion of the two-wire loop circuit and simultaneously to reverse the polarity of the potential difference between said wires; characterized by the fact that said shunt impedances each comprise a conductive impedance in series with a rectifier polarized to block current flow through the impedance by the normal potential difference developed between said wires prior to the simultaneous opening of said relays.

10 2. A control or alarm system as recited in claim 1, wherein each conductive impedance is of resistive type.

25 3. A control or alarm system as recited in claim 1, wherein the relay in one wire of the loop circuit constitutes the major impedance in that wire circuit and the potential on the wire at the sections thereof is substantially that of the source terminal remote from the relay, a resistance is included in the other wire at the central station and remote from its relay, whereby the potential of said other wire along the sections thereof is intermediate that of the source of current.

30 4. An alarm circuit of the type including two wires each connected across a direct current source and with two-pole switches spaced along the two-wire circuit and dividing the same into a plurality of serially arranged sections, said wires extending adjacent each other through the region to be protected, means establishing a normal potential difference between said wires throughout the lengths thereof, and impedances connected between said wires adjacent to each switch and similarly located with respect to the switches and the current source; each impedance comprising a conductive impedance in series with a rectifier polarized to block conduction at said normal potential difference between the wires and means operative upon the simultaneous opening of both wires to reverse the polarity of the potential difference between said wires.

35 5. In an alarm or control system of the type including a two-wire loop circuit connected across a source of direct current, relays in the respective wires at opposite ends of the loop circuit, shunt impedances across the wires and dividing the loop circuit into a plurality of serially arranged sections, means additional to said relays developing a potential difference between the wires along the loop circuit, said shunt impedances each including a conductive impedance in series with a rectifier polarized to block current flow, said relays including contacts operative on simultaneous release of the relays by an opening of both wires of the loop circuit to connect one set of ends of the two-wire circuit into a measuring circuit and simultaneously to reverse the polarity difference between the wires of the two-wire loop circuit.
